FIG-1-

FIG-2-

FIG-3-

Fig. 1 is a front perspective view of a pair of spectacles, showing my new design;

Fig. 2 is a rear perspective view thereof; and

Fig. 3 is a top plan view thereof.

The temples are shown broken away in Figs. 2 and 3 for convenience of illustration.

The dominant features of my new design are shown in full lines in the drawing.

The figures are shaded to indicate contrast in color.

I claim:

The ornamental design for a pair of spectacles, as shown and described.
